UNITED STATES PATENT OFFICE.

JOHN S. FORBES AND ROY H. POSTON, OF FLAT RIVER, MISSOURI.

PERMUTATION-PADLOCK.

1,137,960.

Specification of Letters Patent.

Patented May 4, 1915.

Application filed March 4, 1914. Serial No. 822,468.

To all whom it may concern:

Be it known that we, JOHN S. FORBES and ROY H. POSTON, citizens of the United States, residing at Flat River, in the county 5 of St. Francois and State of Missouri, have invented certain new and useful Improvements in Permutation-Padlocks, of which the following is a specification.

This invention relates to permutation 10 padlocks and one of the objects is to provide a body portion comprising intermediate and permutation disks connected in such a manner as to permit of rotation of the permutation disks to operate the bolt.

15 A further object of the invention is to provide an intermediate disk in which a passage is formed for the guiding leg of the shackle and a recess for the bolt and the locking leg of the shackle, the bolt being held in place in the intermediate or bolt disk 20 by the laterally abutting permutation disks and also moved by rotation of the permutation disks into and held thereby in a shot or locking position.

25 It is a further object of the invention to provide a spring for the bolt so that it will be shot into an unlocking position when the permutation or combination members have been rotated or moved into a position to unlock the device.

30 Further objects of the invention will be more fully described in connection with the accompanying drawing and will be more particularly pointed out and ascertained in 35 and by the appended claims.

In the drawing:—Figure 1 is a view in side elevation illustrative of one form of our invention. Fig. 2 is an edge view thereof. Fig. 3 is a sectional view on line 40 3—3 of Fig. 2, showing the parts in a locked position. Fig. 4 is a view similar to Fig. 3 showing the parts in an unlocked position. Fig. 5 is an inside view of one of the permutation or combination members. Fig. 6 is a 45 perspective view of the improved bolt.

Like characters of reference designate similar parts throughout the different figures of the drawings.

As illustrated, 1 designates the shackle 50 having a relatively long guiding leg 2 and a relatively short locking leg 3. The locking leg 3 is reduced, as indicated at 4 and is provided with a locking notch 5, as clearly shown in Fig. 4. The guiding leg 2 is reduced, as indicated at 6 and its terminal end

is upset or enlarged, as shown at 7 for a purpose which will presently appear.

The body of the padlock includes an intermediate or bolt member 8 which is shown as a disk of circular form and which is provided with a guiding passage 9 for the reduced portion 6 of leg 2 of the shackle. The guiding passage 9 terminates in an opening 10 in which the enlarged retaining end 7 slides. The opening 10 is dimensioned as 60 regards its length, so that when the shackle is in the position shown in Fig. 4, the retaining end 7 will act as a stop to prevent the shackle from being wholly withdrawn, and when the shackle is in the position shown in Fig. 3, the opening 10 is of sufficient length 70 to permit the locking leg to be inserted fully into a locking position.

On each side of the intermediate or bolt disk 8, we dispose permutation disks 11 75 which are preferably of the same diameter with respect to each other and which are of the same diameter with respect to the intermediate bolt disk 8 so that their peripheries will be flush, the permutation or combination disks 11 serving to close the opening 10. Each permutation disk 11 is provided with a bolt-retaining groove 12 which is shown disposed concentrically with respect to the center of the disk in which it is formed so as to 80 constitute an annular groove. Each groove 12 is provided with a notch 13 having an actuating portion 14, the purpose of which will presently appear. We connect the permutation disks 11 with the bolt disk 8, centrally of the same, and by means of a simple 85 form of rivet, as indicated at 15. In order to prevent disassembling of disks, the ends of the rivet 15 are upset, as indicated at 16, and the upset portions will be made so that 90 the permutation disks may be relatively freely rotated with respect to the bolt disk 8. 95

We will next refer to the form of bolt employed and the manner in which the same is operated in connection with the permutation or combination disks 11. The bolt disk 8 is cut away, as indicated at 17, to form a bolt cavity for receiving a bolt 18. The bolt 18 is shaped to be reciprocated in the cavity 17 from the position shown in Fig. 3 100 to the position shown in Fig. 4, and vice versa. The bolt is equal in thickness to the thickness of the bolt disk 8 and is held in place in the cavity by the permutation disks 11. Said bolt 18 is provided with oppositely 105 110

projecting studs 19 which extend into the groove 12 of the permutation disks 11, as indicated in Fig. 3. The bolt 18 is also provided with a locking nose 20 adapted to engage the notch 5. A notch 21, in the bolt 18, receives the upper end of a spring 22 which is fitted in a recessed portion 23 in the bolt disk 8. The spring 22 is tensioned to normally retract the bolt so as to hold the same in an unlocked position and the spring is held in place in the cavity 23 by the permutation disks 11.

Assuming that the parts are in the position shown in Fig. 4, the shackle 1 will be shifted into the position shown in Fig. 3 and one or both, but preferably both of the permutation disks 11 will be rotated in a contraclockwise direction, from the position shown in Fig. 4, so that the actuating portion 14 will engage the studs 19 to cause the bolt to be shot from the position shown in Fig. 4 to the position shown in Fig. 3. It will be seen that the studs 19 move in a straight line and that they will ride upwardly on the actuating portion 14 as the disk 11 or both disks are rotated in a contraclockwise direction until the studs 19 reach the grooves 12, as shown in Fig. 3, in which position the bolt will be locked or retained against movement from engagement with the locking leg of the shackle. In unlocking the padlock, it will be necessary to rotate both of the combination disks 11 until the notches 13 register with the studs 19 to permit retraction of the bolt by the spring 22. This position is shown in Fig. 4 and it will be readily seen that when the shackle is unlocked it can be partially withdrawn, the retaining end 7 preventing the shackle from being wholly detached from the body of the lock.

It is believed that the advantages and utility of our invention will be clearly understood from the foregoing description and while we have herein shown and described one specific form of our invention, we do not wish to be limited thereto except for such limitations as the claims may import.

50 We claim:—

1. In a permutation padlock, a shackle having a guiding leg and a locking leg, a body comprising an intermediate bolt disk having a passage for said guiding leg and a cavity for the locking leg and a bolt-receiving recess intersecting said cavity, a bolt loosely disposed in said recess, a spring normally acting to retract said bolt from engagement with said locking leg, permutation disks abutting opposite sides of said bolt disk and rotatably mounted thereon, said bolt having oppositely projecting studs and said permutation disks having annular grooves for receiving said studs and retaining said bolt in a shot position, and said grooves having

notches for permitting retraction of said bolt from a shot position by said spring.

2. In a permutation padlock, a shackle having a locking leg, a body comprising an intermediate bolt disk having a cavity for the locking leg and a bolt-receiving recess intersecting said cavity, a bolt loosely disposed in said recess, means to retract said bolt from engagement with said locking leg, permutation disks abutting opposite sides of said bolt disk and rotatably mounted thereon, said bolt having oppositely projecting studs, and said permutation disks having annular grooves receiving said studs and notches having actuating portions for shifting said bolt into a locking position.

3. In a permutation padlock, a shackle having a locking leg, a bolt disk having a cavity for said locking leg and a bolt-receiving recess, a bolt in said recess, means normally acting to move said bolt out of engagement with said locking leg, and a permutation disk movable with respect to said bolt plate and having means for shifting said bolt into and retaining the same in a locking position.

4. In a permutation padlock, a shackle having a locking leg, a bolt disk having a cavity for the locking leg and a bolt-receiving recess, a bolt in said recess, and a permutation disk movable with respect to said bolt disk and having means for shifting said bolt into and retain the same in a locking position.

5. In a permutation padlock, a shackle having a locking leg, a bolt disk having a cavity for the locking leg and a bolt-receiving recess, a bolt in said recess, and a permutation disk movable with respect to said bolt disk and having grooved means for shifting said bolt into and retaining the same in a locking position.

6. In a permutation padlock, a shackle having a locking leg, a bolt disk having a cavity for the locking leg and a bolt-receiving recess, a bolt in said recess, and a rotatable permutation disk laterally of said bolt disk and provided with means for retaining said bolt in locked relation with respect to said locking leg.

7. In a permutation padlock, a bolt disk having a cavity for a shackle locking leg and a bolt-receiving recess, a shackle having a locking leg for entrance into said cavity, a bolt in said recess, and a rotatable permutation disk laterally of said bolt disk and having a notched portion for shifting said bolt into locking relation with said leg and a grooved portion for retaining said bolt in locking relation with said leg.

8. In a permutation padlock, a shackle having a locking leg, a bolt disk having a cavity for the locking leg and a bolt-receiving recess, a bolt reciprocable in a straight line of movement in said recess, a per-

mutation disk movable with respect to said bolt plate and having means including a curved groove and a notch for retaining and actuating said bolt, and means carried by 5 said bolt to project therefrom into said grooves and to pass into said notch in the relation hereinbefore set forth.

9. In a permutation padlock, a shackle having a locking leg, a bolt disk provided 10 with a cavity for the locking leg and a bolt-receiving recess, a bolt reciprocable in said recess in a straight line of movement and having actuating studs, permutation disks on opposite sides of said bolt disk, a rivet 15 extending through and rotatably mounting said permutation disk on said bolt disks, and said permutation disks having notches and annular grooved portions coacting with said studs to shift and retain said bolt in 20 locked relation with said locking leg.

10. In a permutation padlock, a shackle having a locking leg, a body adapted to receive said locking leg comprising a bolt disk and rotatably connected laterally abutting 25 permutation disks, and a bolt in said bolt

disk provided with means coacting with said permutation disks for operation of the bolt on rotation of the disks.

11. In a permutation padlock, a shackle having a locking leg, a bolt disk in which 30 said shackle is mounted to be capable of sliding movement, a central member received through said bolt disk, permutation disks rotatably mounted upon said central member laterally of said bolt disk, a bolt 35 mounted in said bolt disk to secure the shackle in a locked relation, and means carried by said bolt to coöperate with said permutation disks to cause release of said bolt and to consequently loosen the shackle as 40 the proper turning adjustment is given to the permutation disks around the member upon which said disks are rotatably mounted.

In testimony whereof we affix our signatures in presence of two witnesses.
